UNITED STATES PATENT OFFICE

ALEXANDER S. KNOWLES, OF CHICAGO, ILLINOIS, ASSIGNOR TO TAR & PETROLEUM PROCESS COMPANY, OF CHICAGO, ILLINOIS, A CORPORATION OF ILLINOIS

METHOD OF COKING LIQUID HYDROCARBONS

Application filed September 9, 1927. Serial No. 218,453.

This invention relates to a new and improved method for the treatment of liquid hydrocarbons for the removal of volatile fractions and the coking of the residue into a form adapted for commercial use. This process is adapted for the treatment of liquid hydrocarbons such as tars derived from the gas industry, coal distillation, wood and other distillation processes and also heavy 10 oils or residues resulting from the distillation or cracking of petroleum or petroleum products. It is adapted for use with these and other materials liquid at normal temperatures or capable of being liquefied by moderate 15 heat.

In previous methods of treatment of such hydrocarbons, the volatiles have been removed to some extent with the formation of a more solid residue, which, however, is only 20 suitable for special uses. These prior methods have been inefficient in that they have not successfully removed a high percentage of the volatile constituents and the residue has been of a comparatively soft sticky nature 25 which renders difficult its removal from the unit in which the treatment takes place, and which also renders its handling and transportation difficult.

In certain of my prior applications, as for 30 example, application Serial No. 153,780, filed December 10, 1926, I have disclosed a method for the treatment of such hydrocarbons in which the solid residue has been combined with coke or similar material.

35 It is an object of the present invention to provide a method of treatment in which the volatiles are driven off and the solids recovered as a hard porous coke substantially free from ash and of considerable commercial 40 value for many purposes.

It is a further object of this invention to provide a method of this character which is adapted for commercial utilization in connection with apparatus of simple design and 45 construction.

Other and further objects will appear as the description proceeds.

I have illustrated somewhat diagrammatically in the accompanying drawings a form 50

of apparatus adapted for carrying out the method of my present invention.

In the drawings—

Figure 1 is a longitudinal section of the apparatus taken on the vertical plane; and 55

Figure 2 is a vertical transverse section.

In the drawings I have shown a form of retort having a floor 11 preferably formed of refractory tile or similar material under which is located a plurality of flues 12. The 60 burners 13 are provided by means of which combustion may be brought about in the flues 12. The flues 12 lead to short downtakes 12' which pass into a waste heat flue 14. The retort chamber 15 contains a basket 16 upon 65 a shaft 17 journaled outside the ends of the retort structure 18. One end of the shaft 17 is provided with a gear 19 by means of which the basket 16 may be rotated. The shaft 17 may be tubular and a pipe 20 is provided by 70 means of which a gaseous fluid may be introduced into the basket through the openings 20' in the hollow shaft. The basket 16 is preferably formed of a heavy wire mesh or other material adapted to permit passage of 75 gases through the basket but to retain broken materials, such as coke, in the basket.

The longitudinal chamber 21, located above the axis of the basket 16, contains a fixed basket 22. In the top of the chamber 80 21 is located a distributing pipe 23 provided with a plurality of spaced nozzles 24 for the distribution of the liquid hydrocarbon. This is fed to the pipe 23 by means of the pipe

25 controlled by valve 26. The passage 27 leads from the upper portion of the chamber 21 and serves for the withdrawal of the volatile products of the process. The lower 85 passages 30 are provided which may be used for the removal of gases or vapors liberated 90 from the heavier material on the floor. The pipes 28 enter laterally into the lower portion of the retort chamber 15 and serve to introduce steam or other gaseous medium as may be desired. The pipe 28 is controlled by 95 valve 29. The end 31 of the chamber may be opened for removal of the basket and the coke on the floor may be removed through door 32.

In carrying out my process the basket 16 100

is partially filled with crushed material such as coke. It is preferably approximately three-fourths filled so as to maintain a large mass of material and yet have sufficient space so that the material is thoroughly turned over and agitated as the basket is rotated. The upper stationary basket 22 is filled with coke or other material suitable for the purpose. The burners 13 are placed in operation and the bottom floor 11 of the retort chamber is thoroughly heated. The temperature to be used varies depending upon the nature of the material being treated and also with the formation of the solid coke-like material upon the floor of the retort chamber. The heavy hydrocarbon to be treated preferably receives a preliminary heating sufficient to bring it to approximately 100 degrees centigrade.

20 The valve 26 is opened and the liquid drops down through the openings 24 upon the coke or other material in the fuel basket 22. The volatiles are drawn off through passage 27 by means of a draft created in any desired manner. This draft causes passage 25 of gases through the liquid-coated coke or other material in the basket 21 which serves to volatilize those fractions which are volatile at the comparatively low temperature present at this point. The liquid drips from the basket 22 on to the basket 16 and on to and through the coke retained in this basket. It will be understood that the temperature gradually increases progressively towards the lower portion of the basket which 30 approaches the heated floor. The gases formed by volatilization in the basket pass through the coke in the basket and are carried off upwardly. The unvolatilized residue 35 due gradually works its way down through the coke in the basket and drips from the lower portion of the basket upon the highly heated floor 11. While the heat of this floor may be varied as above stated, depending 40 upon the grade of material, I have found that temperatures varying from 500 degrees to 1000 degrees centigrade generally are suitable.

50 This liquid falling upon the floor has the remaining volatile content driven off by the high heat of the floor and the residue forms a hard coke-like mass containing a very small percentage of ash and volatile matter. The volatile matter released on the floor from 55 the heavier material there may be drawn off through passage 30 on account of its greater specific gravity. A clearance of about six inches is suitable between the lower side of the basket and the floor 11, although this may 60 be varied depending upon the heat it is desired to apply to the material in the basket and the depth of residue on the floor. It is found in usual practice that the liquid residue distributes itself over the entire floor 65 and does not pile up immediately under the

basket. When the solid residue has formed on the floor to a depth of three to five inches, the process is preferably temporarily stopped and the solid residue removed. It has been found that the coke in the basket becomes coated with the solid residue but does not appreciably grow in size and this coke need only be removed at long intervals to maintain a uniform size and proper percentage of empty space in the basket. The end 70 75 31 of the chamber may be opened for removal of the basket.

It will be apparent that the temperature in the retort will gradually decrease during the accumulation of a layer of coke upon the floor 11 due to the insulating effect of this layer. This decrease in temperature may be compensated for by increase in combustion from the burners 13 so as to maintain the retort temperatures substantially constant if 80 desired. The rotation of the basket may be continuous or intermittent. It is not normally desirable to rotate the basket rapidly as the hydrocarbons should gradually pass down through the material. It will be apparent that the rotation of the basket constantly presents new surfaces of the material to the liquid hydrocarbons falling into the basket and causes the liquid hydrocarbons to be gradually carried down to the zone of 85 higher temperature caused by approach to the radiating floor 11. This rotation is desirable in that it prevents agglomeration of the coke in the basket and also prevents channelling by the gases.

100 During the process, steam or other gases may be introduced through pipe 20 and through the openings 20' into the mass in the rotating basket. This will serve to increase the current of gases released in the basket and carried off through the passage 27. Steam has the advantage of being readily removed from the gases upon their subsequent treatment. Steam may be introduced if desired through the pipes 28 laterally into 105 the retort chamber.

110 It will be understood that the gaseous products of the process may be treated in any desired customary manner. They may be passed through a series of condensers operating at different temperatures so as to remove separately various condensable products. The steam may also be condensed out in this manner. The remaining gas may be used for any desired purpose. Steam has 115 the disadvantage, however, of cooling the retort chamber. If desired, therefore, instead of steam any suitable gases may be used for introduction through pipes 20 or 28 to cause the gaseous circulation through the retort. 120 A portion of the spent gases derived from the combustion below the retort floor may be utilized if the final gaseous product of the process is not required to be of high heat 125 value. If desired, a portion of the gases 130

remaining after the condensation processes have taken place, may be returned to the retort through pipe 20 or 28 and recirculated.

While I have specifically referred to coke as the material to be used in the baskets 16 and 22, it will be apparent that other materials may be used, such for example, as crushed pumice stone, or metal, or any other material which may act as a catalyst in the breaking down of the heavier hydrocarbons. The size to which the material used is to be crushed may be varied with the viscosity of the material being treated. With a relatively liquid material small pieces of material may be used so as to retard the passage of the liquid through the retort and afford ample time for volatilization. With a relatively heavy liquid larger material may be used in the baskets, as this material will flow more slowly. The rapidity of rotation of the basket 16 also may be varied depending upon the viscosity of the liquid being treated and the time required for the distillation of its volatile constituents. Temperature control in the retort can also be effected by control of the combustion in the heating flues below the retort floor as well as by the rapidity of the circulation of gases through the retort and the temperature of the gases introduced into the retort for this circulation. It has been found in the operation of a plant of this character that there is not only the distillation of the volatiles from the liquid, but, where suitable materials are being operated upon, there is a definite cracking of the heavier constituents into lower boiling fractions. This cracking takes place not only in the basket but during the deposit of the liquid dripping from the basket on to the floor.

It will be apparent, therefore, that my process offers a very wide control of operating conditions so as to adapt it to treatment of a wide variety of hydrocarbons whether normally liquid or capable of liquefaction at moderate temperatures. There is a complete recovery in merchantable form of the liquid being treated. Although the oils recovered may normally be considered as the primary product of the process, the gas has fuel value and the coke-like product formed on the floor of the retort is of high commercial value. This latter fact is one of the features which particularly distinguish my process. In prior processes much of the solid residue has been of little commercial value and thus there is a lesser return from a considerable percentage of the carbon present in the liquid being treated. The solid product of my process is a hard coke-like material which may be used as a metallurgical fuel and for many other purposes and is readily salable at high prices.

I claim:

1. The method of treating heavy liquid

hydrocarbon material which comprises passing said material through a bed of loose solid material that is substantially insoluble in said liquid hydrocarbon material and substantially infusible at a coking temperature, progressively increasing the temperature of the material by passing it downwardly through said bed, agitating said material during the passage of the liquid hydrocarbon material, depositing the liquid residue in a layer upon a heated surface, and distilling and carbonizing the liquid on said surface. 70

2. The method of treating heavy liquid hydrocarbon material which comprises passing said material through a bed of loose solid material that is substantially insoluble in said liquid hydrocarbon material and substantially infusible at a coking temperature, progressively increasing the temperature of the material by passing it downwardly through said bed, agitating said material during the passage of the liquid hydrocarbon material, passing a gaseous current through said material to carry off the volatiles from the hydrocarbon material, depositing the liquid residue 80 in a layer upon a heated surface, and coking the residue on such surface. 85

3. The method of treating heavy liquid hydrocarbon material which comprises progressively heating the material by passing said material downwardly through a mass of loose coke which is progressively hotter toward the bottom, agitating the coke during the passage of the hydrocarbon material, permitting the liquid residue to drip upon a surface heated to a coking temperature, and coking the residue on such surface. 95

4. The method of treating heavy liquid hydrocarbon material which comprises passing said material downwardly through a bed of loose coke, permitting the liquid hydrocarbon material to drip from said bed of coke to a second bed of coke, agitating the second bed of coke during the passage of the hydrocarbon material, permitting the liquid residue to drip from the second bed upon a surface heated to a coking temperature, and coking the residue thereon. 105

5. The method of treating heavy liquid hydrocarbon material which comprises progressively heating the material by distributing the liquid over a bed of loose solid material that is substantially insoluble in said liquid hydrocarbon material and substantially infusible at a coking temperature, heating said bed from below the same, permitting the unvolatilized liquid residue to drip from the bed upon a surface heated to a carbonizing temperature, driving off the remaining volatiles and forming a solid carbonaceous mass on the surface, and periodically removing said mass. 115

Signed at Chicago, Illinois, this 7th day of September, 1927.
